UNITED STATES PATENT OFFICE.

FRED SELL, OF MILWAUKEE, WISCONSIN, ASSIGNOR OF ONE-HALF TO
WILLIAM KLAESER, OF SAME PLACE.

STOCK-CAR.

SPECIFICATION forming part of Letters Patent No. 321,860, dated July 7, 1885.

Application filed October 14, 1884. (No model.)

To all whom it may concern:

Be it known that I, FRED SELL, of Milwaukee, in the county of Milwaukee, and in the State of Wisconsin, have invented certain new and useful Improvements in Cattle-Cars; and I do hereby declare that the following is a full, clear, and exact description thereof.

My invention relates to improvements in cattle-cars, and will be fully described hereinafter.

In the drawings, Figure 1 is a vertical longitudinal section through the center of a cattle-car box fitted with my improved devices in position for use. Fig. 2 is a vertical cross-section of part of a car showing my devices in like position, and Fig. 3 is a like view of the same, showing the trough and hay-rack as raised up when not in use.

The object of the present invention is to simplify the construction of the device for which Letters Patent No. 296,842 were granted to me jointly with William Klaeser, of Milwaukee, Wisconsin, April 15, 1884, so as to materially reduce the cost of its manufacture, and to also render the same more effective, more promptly and easily manipulated, and less liable to get out of order.

A is the car-body; B, the hay-rack, and C represents the water-trough. This latter is suspended in any suitable manner to the endless chains D D, which are mounted in the top and sides of the car-box on sprocket-wheels d d' d', journaled in bearing-boxes e e' e', respectively. The upper wheels, d d', are keyed onto the longitudinal shaft D', the ends of which are journaled in the bearing-boxes e e', fitted in the upper ends of the brackets E, fastened in the roof A' of the car-box so as to carry the chains D astride, as it were, of the car sides A², suitable perforations being made for that purpose in the said parts. Either one or both of the said sprocket-wheels may be provided with a pawl-ratchet, d², and a crank-handle, d³, by means of which the shaft D' may be operated to raise or lower the trough C and the hay-rack B. This latter consists of the sliding base-pieces b b, the outer ends of which are vertically perforated to be adapted to slide up or down along the guide-rods F F, fitted in the roof and bottom of the car-box at a slight distance from the inner face of the sides A².

The inner portions of the base-pieces b are

vertically flattened and perforated to receive 55 the lower bar, b', of the hay-rack, bearing freely therein. The upper bar, b², of the said rack rests against the upper edge of the curved-up lower end of the brackets G G, fitted by bolts gg in the roof A', and depending therefrom on a suitable incline toward the car sides.

The operation of my device is substantially the same as disclosed in the previously-named patent.

The location of the hoisting and lowering gear has been changed for greater convenience, and the substitution of the endless chains for the screws, besides adding considerable advantage on account of their being 60 adapted to work more rapidly, has materially reduced the cost of the device.

Having thus described my invention, what I claim as new, and desire to secure by Letters Patent, is—

1. In a cattle-car, the combination of a water-trough suspended on endless chains mounted, substantially as herein described, in the roof and sides of the car-box, mechanism, substantially as described, to raise or lower the 75 same as desired, a folding hay-rack adapted to slide in guide-rods of the car-box, and supporting-brackets depending from the car-roof, substantially as and for the purpose set forth.

2. In a cattle-car, the combination of the endless chains D, carrying the water-trough C, with the car-roof A', provided with bearing-brackets E, shafts D', carrying sprocket-wheels d d', pawl-ratchet d², and hand-crank d³, and box sides A², provided with bearings e e', and sprocket-wheels d' d', substantially as shown and described, and for the purpose set forth.

3. In a cattle-car, the hay-rack B, having 95 sliding hinge-pieces b b, in combination with the roof and bottom of car-box having guide-rods F F, brackets G, and chains D, provided with hoisting mechanism and carrying the trough C, substantially as shown and described, and for the purpose set forth.

In testimony that I claim the foregoing I have hereunto set my hand, at Milwaukee, in the county of Milwaukee and State of Wisconsin, in presence of two witnesses.

Witnesses: FRED SELL.

S. S. STOUT,
